AUXILIARY HOUSING FOR PICKUP TRUCKS

Harold G. Phillips, Rte. 3, Box 103A,
Pasadena, Md. 21122

Filed Mar. 24, 1975, Ser. No. 561,543

Term of patent 14 years

Int. Cl. D12—16

U.S. Cl. D12—156

FIG. 1

FIG. 2

FIG. 3

FIG. 1 is a front isometric view of an auxiliary housing for pickup trucks showing my new design;

FIG. 2 is a front isometric view thereof to a reduced scale; and

FIG. 3 is a rear isometric view thereof to a reduced scale.

I claim:

The ornamental design for an auxiliary housing for pickup trucks, substantially as shown.
